UNITED STATES PATENT OFFICE.

EMELINE B. VROOMAN, OF CHICAGO, ILLINOIS.

DESIGN FOR A SINK-STRAINER.

SPECIFICATION forming part of Design No. 24,457, dated July 2, 1895.

Application filed June 7, 1895. Serial No. 552,033. Term of patent 14 years.

To all whom it may concern:

Be it known that I, EMELINE B. VROOMAN, a citizen of the United States, residing at Chicago, in the county of Cook and State of Illinois, have invented and produced a new and original Design for Sink-Strainers, of which the following, in connection with the accompanying drawings, is a full, clear, and exact specification.

In the said drawings, Figure 1 represents a sink-strainer in perspective embodying my design. Fig. 2 is a plan view thereof, and Fig. 3 is a front view.

The essential features of my design consist of the funnel-shaped body portion A, having the truncated or abrupt lower end B and the flange or laterally-projecting portion C at its upper rear side or edge.

The body portion A is substantially funnel-shaped, its upper side being flared to a wide angle, while its lower end B is cut off abruptly, as shown more clearly in Fig. 3. The front or outer side of the strainer-body portion A is bowed or substantially circular, while the

rear side is formed at an angle D. The upper 25 rear side of the body portion is also angular, and the flange C projects laterally and rearwardly in substantially a horizontal direction, the forward ends of the flange C being tapered off, so as to gradually run into the curve of 30 the upper forward side of the strainer, thus making the flange C at each side thereof substantially V-shaped. In the apex of the angle formed by the two side portions of the flange C is formed a perforation c.

The forward outer side of the body portion A is provided with a number of upright radially-arranged slits or slots a.

Having thus described my invention, what I claim as new therein, and desire to secure by 40 Letters Patent, is—

The design for sink-strainers substantially as herein shown and described.

EMELINE B. VROOMAN.
